UNITED STATES PATENT OFFICE.

ELIAS WIRTH-FREY, OF AARAU, SWITZERLAND.

ABSORPTION REFRIGERATING MACHINE.

Application filed June 25, 1923, Serial No. 647,733, and in Germany January 5, 1923.

This invention relates to improvements in refrigerating machines or apparatus of the absorption type.

It is known that refrigerating machines of this class working intermittently by means of a generator-absorber are particularly suited for household purposes and for similar use on a small scale, owing to the fact that no gas compressor or pumps are required in connection therewith.

The great drawback in machines of this kind as hitherto constructed is that the evaporator gradually becomes filled with a residue consisting of the cooling agent and the absorbing liquid used with it. In the generating operation part of the less volatile absorbing liquid naturally passes over together with the more volatile cooling agent, and this results in the evaporator containing a constantly increasing amount of residual liquor. In consequence of the increasing proportion of absorbing liquid therein, the vapour pressure is reduced and this liquor consequently fails to evaporate at the absorption pressures at which the apparatus works. Gradually therefore, the evaporator becomes filled up with residual liquor, and the exchange of heat between the evaporator and the absorber may eventually stop entirely.

Attempts have been made to obviate this defect by interposing an auxiliary cooler between the generator and the condenser and condensing mainly the evaporated absorbent therein. If, in spite of this, some of the absorbing liquid passes into the evaporator, it must be discharged back to the absorber, either by means of suitable piping and valves, an operation which involves a certain amount of attendance and the provision of fittings, or by heating the evaporator externally in order to raise its temperature, thereby also causing the residual liquor to evaporate.

But means of this kind are not admissible in small refrigerating machines which are usually attended by servants. On the contrary, it is imperative to construct them so as to operate automatically.

The object of the present invention is to provide an automatic refrigerating machine, that is to say, a refrigerating apparatus in which the aforementioned drawback is removed by causing the liquid settling at the bottom of the evaporator to return automatically to the absorber under the action of gravity. This is preferably effected by means

of an overflow device connecting the evaporator with the absorber in a suitable manner.

In the accompanying drawing one embodiment of my invention is shown diagrammatically by way of example.

The refrigerant expelled from the generator-absorber 1 passes into the condenser 2, is there liquefied and then flows from the condenser 2 into the evaporator 3. During the subsequent cooling operation the pipe 5 is closed and the gas formed in the evaporator 3 flows through the pipe 4 back into the absorber 1. The two pipes or conduits may be combined if desired, but there is no necessity for doing so.

Any absorbing liquid present in the liquor passed into the evaporator 3 remains there and, therefore, towards the end of the evaporating process a residue of liquor incapable of further evaporation is left in the evaporator 3. This residue could be withdrawn from the evaporator by means of a valve fitted at the bottom of the evaporator or by evaporating it by heating the evaporator externally but both methods as already mentioned are not admissible, the former because of the attendance required and the necessity of having a hand controlled valve member, and the latter because the apparatus is intended for cooling and not for heating purposes.

Now, my invention relies upon the fact that the liquefied cooling agent has a lower specific gravity than the absorbing liquid and the residual liquor therefore has a correspondingly higher or specific gravity. The residual liquor can therefore be left in the evaporator for a time and the apparatus allowed to continue in operation. As the cooling agent is lighter than the residual liquor, it does not mix with it to any appreciable extent. In order to facilitate the separation of the two liquors, however, the bottom of the evaporator is formed as a sump 6 where the residual liquor can settle, whilst the cooling agent forms a layer above it. The sump 6 is in open communication with the absorber 1 by means of the by-pass 7.

The overflow level 11 of the by-pass 7 is a little above the normal highest level of the liquor in the evaporator 3, when no absorbing liquid is present therein. In proportion as the absorbing liquid is distilled over into the evaporator the level of the column of liquid in the evaporator rises, and as soon as a certain limit is passed, its weight causes a

corresponding amount of the bottom layer of residual liquor to return through the by-pass 7 into the absorber 1. The pipe 7 being connected up to the bottom of the evaporator, 5 only the liquid contained in the sump 6, that is to say the residual liquor consisting mainly of the absorbing liquid, will be returned to the absorber. The operation is entirely automatic, and no liquid is returned to the absorber, unless some absorbing liquid gathers 10 in the sump 6, and no attention is required to ascertain if any absorbing liquid has collected in the evaporator and has to be discharged therefrom.

15 The sensitiveness of the apparatus may be increased by reducing the cross-sectional area of the evaporator in the region 8 of the overflow level 11, so that only a small amount of excess liquid will suffice to cause the by-pass 20 to act. The larger space 9 above the reduced part 8 may with advantage be used for separating the gaseous agent from the liquid during the evaporating operation.

The intensity of discharge may be still further increased by giving the pipe 7 a special 25 siphon shape, the horizontal top portion and the descending limb being narrower than the rising limb of the siphon whereby, when the liquid in the evaporator rises above a certain 30 level, a sudden evacuation is effected. The quantity of liquid discharged from the evaporator 3 may be limited either by connecting the descending limb of the siphon pipe with the wider absorption pipe 4 so that the siphoning action ceases when the liquid reaches 35 a certain level 14, or by providing an auxiliary or relief-pipe connecting the horizontal top portion of the siphon 7 with the evaporator 4 so that the siphon will be broken at the 40 top when the liquid in the evaporator falls to the level 12.

From the foregoing, it is believed that the advantages and novel features of my invention will be readily understood and therefore 45 further detailed description is deemed unnecessary.

In putting my invention into practice I find that the preferred embodiment shown herein diagrammatically is the most practical 50 and efficient arrangement, but realizing that certain conditions will necessarily vary when the invention is carried out in practice, I desire to emphasize the fact that various

changes in the details of construction and arrangement and in the proportions of the parts 55 may be resorted to when required without departing from the scope of the invention. In particular I wish it to be understood that it is not absolutely necessary for the return pipe 4 to be connected with the by-pass 7 or 60 the like, and furthermore, that there is no necessity, in view of the object and scope of my invention, for keeping closely to the particular mode of construction, connection and operation of the parts shown diagrammatically in the drawing by way of example only. 65

What I claim is:

1. An absorption refrigerating machine comprising in combination a generator-absorber for vaporizing a relatively volatile 70 cooling agent from a relatively low volatile absorbing medium, a condenser for condensing said vaporized cooling agent, an evaporator arranged at a higher level than said generator-absorber, said evaporator comprising 75 upper and lower portions, a constricted passage between said upper and lower portion, means for transferring condensate from said condenser to said upper portion, a suction pipe connecting said upper portion with said generator-absorber, and an unobstructed continuously open residue return line from said lower portion to said suction pipe, said return line being capable of allowing the transfer 80 from the bottom of said lower portion of the contents in the lower part of said lower portion, on the level of the contents of the evaporator being in line with the said constricted passage. 85

2. An absorption refrigerating machine 90 comprising in combination a generator-absorber for vaporizing a relatively volatile cooling agent from a relatively low volatile absorbing medium, a condenser for condensing said vaporized cooling agent, an evaporator, said evaporator comprising upper and 95 lower portions, a constricted passage between said upper and lower portion, means for transferring condensate from said condenser to said upper portion, a suction pipe connecting said upper portion with the generator-absorber, a sump in said lower portion and an unobstructed siphon connection from said sump to said suction pipe. 100

In witness whereof I affix my signature.
ELIAS WIRTH-FREY.
